UNITED STATES PATENT OFFICE

ALEXANDER HORVATH, OF CHICAGO, ILLINOIS

METHOD OF FORMING CRYSTALS

Application filed May 9, 1928. Serial No. 276,350.

This invention pertains to the art of crystal forming, and particularly to method of forming crystals for cases. The particular embodiment of applicant's invention disclosed in this application pertains especially to a method of forming crystals for watch cases and the like. It is well known that watch cases, and particularly those worn on the wrist, are of many different sizes and shapes. 5 Whenever a crystal is broken same is, in many cases, very difficult to replace. This is particularly true should the crystal be of an odd size or shape. Furthermore, watch cases, being manufactured of relatively light material, the portion thereof in which the crystal is mounted often becomes warped or otherwise out of shape, thus making it very difficult or impossible to secure therein a crystal, although the crystal may be of the correct size and shape for that particular design of watch. Furthermore, the large variety of watch cases in use entails the necessity of a very large and varied stock of crystals in order that a particular demand may be met. 10 Owing to the fact that a large portion of such a collection of crystals is necessarily dead stock, the price of an individual crystal is greatly increased. Furthermore, should a crystal be ground to size, same being curved generally over its entire area, same in many cases will bind the outer tips of the hands of the watch. Should this portion be ground away to make room for the hands, a certain aberration results due to varied thicknesses 15 and angles of the ground portion. An object of applicant's invention, therefore, is the production of a method of forming crystals, and particularly crystals for watch cases by means of which method a crystal may be readily formed from a blank piece of material, said crystal conforming to the exact shape of the opening in the casting in which same is to be secured. A further object of applicant's invention is the production of a method for the production of a crystal of any desired height, thus allowing any desired clearance for the hands of the watch. A further object is the production of a crystal that is of the same height throughout except for relatively narrow edge portions, by 20 means of which the crystal is secured to the case or that is of any desired variation in height or shape. A further object is the production of a method for forming crystals of any desired size, shape, pattern or design. 55 A further object of applicant's invention is the production of crystals that are of low cost, unbreakable, of correct size, that will not bind the hands of a watch, and that are highly satisfactory for their intended purposes. 60 Many other objects and advantages of the construction herein shown and described will be obvious to those skilled in the art from the disclosure herein given. 65 Applicant's invention embodies apparatus for holding the device for which the crystal is to be formed. The particular device shown in this application is a watch case. Same is held between jaws mounted on a table having heating means. The heating means shown is an electrical heating element. The table on which the jaws are mounted is preferably pivoted to its base so that the watch case may be revolved during the forming of the crystal. The crystal is preferably 70 formed from a blank of celluloid or similar material. Means are provided for obtaining the desired width of the blank and same is then cut from the strip of material. Means are provided for holding the blank in position above the opening in the watch case in which the crystal is to be set or mounted when finished. The heating element is then energized for a short period of time and preferably to such extent that the heat supplied 75 to the jaws and other parts of the apparatus will eventually cause the celluloid blank or other material to soften. The heat is then preferably turned off and the blank formed to size by means of a forming tool preferably 80 having a small ball at its end. Same is used to press the celluloid blank down into the opening in the watch case around the borders thereof and to otherwise form the crystal. The height of the finished crystal is regulated 85 by the amount that the blank is depressed into the opening. Except for the portions around the border of the opening, which may be arcuate or angular according 90 to the shape of the forming tool, the balance 95 100

of the crystal may be plain or any desired shape as required, or according to choice. After the crystal is formed, the blank is withdrawn and the crystal cut from the blank 5 by following the outline impressed thereon by the edge of the opening in the watch case or the forming tool may be provided with a projection in the form of a pin, blade, disc, or similar means which scratches or cuts the 10 blank while same is in place and the crystal is broken therefrom preferably after same cools. The edges of the crystal are then preferably beveled somewhat in order that same may anchor themselves in the groove about 15 the opening in the watch case. A cement such as celluloid cement may be used about the edges of the crystal in securing same in place if desired, particularly if the watch case is to be made water-proof. However, the 20 cement is not necessary to secure the crystal in place.

The watch case thus forms the pattern or die for its own crystal. It is thus seen that a crystal of any shape, size, design or pattern 25 may be readily produced at low cost.

To this end my invention consists in the novel construction, arrangement and combination of parts herein shown and described, and more particularly pointed out in the 30 claims.

In the drawings, wherein like reference characters indicate like or corresponding parts:

Fig. 1 is a plan view of the device;
35 Fig. 2 is a section on line 2—2 of Fig. 1;
Fig. 3 is a section on line 3—3 of Fig. 2;
Fig. 4 is a section on line 4—4 of Fig. 2;
Fig. 5 is a fragmentary top plan view of
the device showing a watch case in position;
40 Fig. 6 is a plan view of a blank of celluloid
or other material;

Fig. 7 is a sectional view illustrating a step
in the formation of the crystal;
Fig. 8 is a plan view of a blank with the
45 crystal formed therein; and

Fig. 9 is a sectional view illustrating the
finished crystal mounted in a watch case.

Referring now to the drawings, in which the preferred embodiment of the apparatus 50 employed in the production of a crystal is shown, 1 is a base upon which is pivotally mounted a member 2 preferably comprising a lower portion 3 forming with the base 1 an enclosure 4 and an upper portion 5 preferably 55 of somewhat lesser diameter. Mounted on the portion 5 is the table 6 which forms a support for diametrically opposed jaws 7 and 8.

Mounted on the base 1 and within the enclosure 4 are two brushes 9 and 10 which may be connected to a source of electrical energy through conductors 11 and 12, respectively. The brushes 9 and 10 and the conductors referred to and the connectors therefor are suitably insulated from the base 1. On the up-

per wall of the enclosure 4 is preferably positioned a sheet of insulating material 13 upon which is mounted rings 14 and 15. Rings 14 and 15 are contacted by the brushes 9 and 10, respectively, and are so formed and positioned that the brushes 9 and 10 remain in contact therewith when the member 3 is rotated about its pivot 16 on the base 1. The portion 5 is tubular, and intermediate the ends thereof is preferably positioned a transverse wall 17 which supports the heating element 18. One end of the heating element 18 is connected to the ring 14 preferably by means of a rod 19 having one end secured to the ring 14 and its other end secured to one end of the heating element 18. The other end of the heating element 18 is connected in a similar manner to the ring 15. If desired, heat insulating material 20 may be positioned in the bottom of the member 5. The table 6 is shown with a downwardly extending tubular portion 21 which encloses the upper end of the portion 5 and is secured thereto preferably by means of the screws 22 (see Fig. 3). A strip of heat insulating material 23 is preferably positioned about the heating element 18 and adjacent the wall of the portion 5. Same is in the preferred form spaced from the transverse plate portion 24 of the table 6.

The jaws 7 and 8 have extensions 25 and 26 pivotally engaging same which are externally threaded and pass through and engage internal threads in ears 27 and 28 on the table 6. On the top face of each jaw are preferably positioned spaced, inverted cone-shaped, blank securing members 29. These members 29 on one of the jaws are provided with pointed projections 30, the purpose of which will be hereinafter set forth. The base 1 may be secured to a table, bench or other support by means of screws 31 if so desired.

A crystal is formed as follows: First a watch case without the movement is placed between the jaws. A blank piece of celluloid or similar material is placed in the position shown in dotted lines at 32 in Fig. 2. Same is slightly depressed onto the points 30 on the members 29 on one of the jaws. This leaves guide marks 33 (see Fig. 6). The blank is then cut along a line passing through these two marks. The blank is now of suitable width such that opposite edges of same may be forced under the inverted conical shaped members 29 on the opposed jaws as shown in Figs. 5 and 7. The blank is thus secured in position above the watch case or other device which is to form the pattern or die for the crystal. The heat is now applied for a desired length of time which may be determined by experiment. The desired amount of heat is that which will eventually soften the blank such that same may be readily formed. A forming tool 34 having an end 35 of any desired shape is then

pressed against the blank following the contour of the opening in the case. The forming tool 34 is preferably held at an angle as shown in Fig. 7. The depth to which the center portion 36 of the crystal may be formed (which corresponds to the height of the finished crystal) is determined generally by the angle which the forming tool 34 makes with the horizontal. The greater this angle, the 10 deeper the portion 36 will generally be depressed. However, this is dependent among other things upon the amount of pressure applied and the particular manner in which the operator uses the device. It is, however, 15 understood that the portion 36 may be depressed any desired amount and thus the finished crystal may have any desired height. The forming tool 34 may be beveled at the other end 37 and may be used in pressing 20 the finished crystal in place in the case.

After the crystal is formed the blank with the crystal therein has the appearance shown in Fig. 8. The crystal is now cut therefrom along the line 38. The edges of the crystal 25 may then be beveled if desired as shown at 39 in Fig. 9. This is generally done with a file or other means. This beveling is for the purpose of forming a circumferential edge on the crystal conforming somewhat to the 30 groove in the watch case, so that the crystal may be better secured in position.

However, the same forming tool or a similar one may be provided with a pin or blade 40 which when the forming end thereof is 35 caused to trace or retrace its path along the edge of the bezel, the pin or blade 40 will scratch or cut the blank such that when the blank cools, the finished crystal may be readily broken therefrom.

40 It is readily seen that a crystal of any desired size or shape may be readily and quickly made and at a cost much lower than heretofore. It is understood that other forms of heating means may be employed and that the 45 invention is not necessarily limited to the making of watch crystals but can be used in making crystals or similar articles for many other purposes. Should a crystal when finished or later after it has been in use, be 50 found slightly too small for its opening, same may be readily enlarged by merely laying same on a warm surface such as the table 6 and then applying slight pressure on the outer face of the crystal.

55 Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

65 1. A method of making a crystal for an

opening in a bezel which consists in placing a piece of transparent celluloid material on the bezel in which the opening is formed and in which the crystal is to be positioned, applying heat to soften said material, pressing the material into said opening to form an outline of the opening and an offset portion on said material, and removing from said piece of material the portion thereof defined by said outline.

2. A method of making a crystal for an opening in a bezel which consists in placing a piece of transparent celluloid material on the bezel in which the opening is formed and in which the crystal is to be positioned, applying heat to soften said material, pressing the material into said opening to form an outline of the opening and an offset portion on said material, removing from said piece of material the portion thereof defined by said outline, and thereafter beveling the edges of said portion.

In testimony whereof, I have hereunto signed my name.
